UNITED STATES PATENT OFFICE.

CLETUS M. PUETZ, OF MANTADOR, NORTH DAKOTA.

LADDER HINGE FOR SILO DOORS.

Application filed June 8, 1923. Serial No. 566,775.

To all whom it may concern:

Be it known that I, CLETUS M. PUETZ, a citizen of the United States of America, residing at Mantador, in the county of Richland and State of North Dakota, have invented certain new and useful Improvements in Ladder Hinges for Silo Doors, of which the following is a specification.

This invention relates to certain new and useful improvements in ladder hinges for silo doors and has particular reference to a plurality of ladder sections, each associated with an independent silo door with each ladder section formed of hinged members connected to the frame of the silo and the adjacent door to be swung inwardly of the side wall of the silo through the door opening when the door is in an open position.

The invention further embodies in a ladder hinge for silo doors of the above type, the provision of a weight adapted for selective connection with the desired door for holding the same in an open position elevated and inwardly of the side wall of the silo.

Another object of the invention comprises in connection with a silo door construction of the above type, the provision of a locking device for retaining the silo doors in a closed position.

With these general objects in view and others that will appear as the nature of the invention is better understood, the same consists in the novel construction, combination and arrangement of parts hereinafter more fully described, illustrated in the accompanying drawings, and pointed out in the appended claims.

In the drawings forming a part of this application and in which like designating characters refer to corresponding parts throughout the several views;

Figure 1 is a side elevational view of a silo constructed in accordance with the present invention, showing the independent vertically spaced door opening with one of the openings closed by the improved ladder hinge and silo door,

Figure 2 is an enlarged fragmentary side elevational view of the silo showing a door in closed position with the ladder hinge associated with the wall of the silo and the door, and further showing the devices for retaining the door in a closed position,

Figure 3 is a cross sectional view taken on line 3—3 of Figure 2 showing a portion

of the ladder hinge connected to the side wall of the silo adjacent the upper end of the door opening,

Figure 4 is a cross sectional view taken on line IV—IV of Figure 2 showing the lower portion of the ladder hinge connected to the silo door and the locking devices for retaining the door in closed position,

Figure 5 is a vertical sectional view taken on line V—V of Figure 2 showing the position of the ladder hinge with respect to the silo wall and closure door.

Figure 6 is a detail sectional view similar to Figure 5 showing the door in an open elevated position inwardly of the side wall of the silo,

Figure 7 is a fragmentary front elevational view of one of the doors showing one of the locking devices therefor, and

Figure 8 is a detail sectional view taken on line VIII—VIII of Figure 1 showing the weight and cord with the pulley guides therefor for maintaining the door in an open elevated position.

Referring more in detail to the accompanying drawings, and particularly to Figure 1, there is illustrated a silo embodying a vertical cylindrical wall 1 provided with vertically aligned spaced door openings 2 with an independently operating closure door 3 for each opening, while the silo has its usual cover wall 4.

Each closure door 3 has an independent ladder hinge construction associated therewith, the door 3 being suitably braced by cross bars 5 and 6 at the upper and lower ends thereof, and an intermediate cross brace bar 7 as clearly illustrated. The upper end of each ladder hinge construction is associated with the wall 1^a of the silo between adjacent door openings 2 as shown in Figures 3, 5 and 6, a U-shaped strap bearing 8 being secured to the wall section 1^a adjacent each side of the door opening, the strap bearing 8 carrying a bearing shaft upon which the inner end of a curved bracket arm 9 is pivotally mounted, spacing collars 10 being associated with the mounting of the inner end of the bracket arm 9 for holding the same properly positioned against lateral shifting movement. The mounting for the lower end of each ladder hinge construction embodies a U-shaped bracket 11 secured adjacent each end of the cross brace bar 7 with a straight lever arm 12 carrying a journal hub 13 upon the inner end thereof that

is received within the U-shaped bearing 11 and is journaled upon the shaft 14 that is axially shiftable in the bracket 11 as clearly shown in Figures 4 and 7. A link 15 is 5 pivotally connected at its opposite ends as at 16 and 17 to the adjacent ends of the bracket arms 9 and 12. A ladder step 18 extends between the curved portion of the upper bracket arm 9 as shown in Figure 5, while 10 a second ladder step 19 is anchored to the pivotal connection 16 between the lower bracket arms 12 and the connecting link 15. When the door 3 is in a closed position as 15 illustrated in Figures 2 and 5, the lower bracket arms 12 occupy a horizontal position with the connecting link 15 being vertically disposed, this disposition of the element of the ladder hinge construction presenting the straps 18 and 19 at points outwardly of the side wall 1 of the silo, and as the closure doors 3 are arranged in close proximity as illustrated in Figure 1, a continuous ladder construction is provided for 20 extending the entire height of the silo exteriorly thereof.

To maintain the doors 3 in a closed and locked position, each axially shiftable shaft 14 constituting the inner bearing for the lower bracket arm 12 of the ladder hinge 30 construction carries a cam head 20 upon the outer end thereof and a crank handle 21 upon the inner end, the shaft 14, when the doors 3 are in a closed position as illustrated in Figure 3, being axially shiftable to present the cam heads 20 laterally of the door 35 openings 2 for engagement with face plates 22 secured to the outer face of the wall 1 of the silo as clearly shown in Figure 2. Upon axially shifting the shaft 14, and subsequently 40 rotating the same, the cam heads 20 are moved into frictional binding engagement with the face plate 22 for retaining the doors 3 closed and locked within the openings 2.

45 A pulley guided cord and weight device is selectively associated with each of the doors 3, the inner upper edge of each door being provided with an eye bolt 23 that is selectively engaged by a hook 24 carried by one 50 end of the cord 25, the cord being positioned inwardly of the door opening 2 and passing over a pulley 26 supported upon the inner face of the side wall 1 of the silo above the upper door opening 2 as shown in Figure 1, 55 the cord passing through an opening 27 in the silo wall and then directed over pulleys 28 and 29 supported upon the outer face of the silo wall with a weight 30 carried by the outer lower end of the cord as shown in Figure 1. In opening any of the doors 3, the 60 hook 24 carried by the cord is secured to the eye 23 upon the door, the shaft 14 being then rotated to disengage the cam heads 20 from the face plate 23, and thereafter axially 65 shifted to position the cam heads 20 in-

wardly of the side walls of the door openings, at which time the door 3 will be elevated inwardly of the side wall of the silo to the position shown in Figure 6, the upper bracket arms 9 of the ladder hinge construction pivoting upon the pins carried by the bracket 8 as will at once be obvious.

When the silo is filled, the cord 25 is secured to the uppermost door 3 and a person ascending the steps 18 and 19 upon the ladder hinge construction releases the locking devices associated with said door, and pressure inwardly upon said door will displace the material abutting the same and permit the weight 30 to elevate the door to open position as shown in Figure 6. In a like manner, the succeeding lower doors are opened and if necessary a person may enter an open door and remove only a small portion of the material from the next lower door to permit free movement thereof inwardly of the silo, it being understood that the operating cord 25 is selectively attached to the successive doors. To restore the doors 3 to their closed positions, the same are lowered against the pressure of the weight 30, the ladder hinge construction being projected through the door opening 2 for assuming the position exteriorly of the silo as illustrated in Figure 5 to be locked by the cam heads 20 in a rigid position.

While there is herein shown and described what is believed to be the preferred embodiment of the invention, it is nevertheless to be understood that various forms, modifications and arrangements of the parts may be made without departing from the spirit and scope of the invention as claimed.

What is claimed as new is:—

1. In a silo, wherein the silo wall is provided with vertically aligned spaced door openings, and wherein a separate door is associated with each opening, a ladder hinge construction carried by each door and embodying bracket arms pivoted to the silo wall between adjacent door openings, bracket arms pivotally connected to the door, and link connections between said bracket arms.

2. In a silo, wherein the silo wall is provided with vertically aligned spaced door openings, and wherein a separate door is associated with each opening, a ladder hinge construction carried by each door and embodying bracket arms pivoted to the silo wall between adjacent door openings, bracket arms pivotally connected to the door, link connections between said bracket arms, and means for holding the door in a closed and locked position.

3. In a silo, wherein the silo wall is provided with vertically aligned spaced door openings, and wherein a separate door is associated with each opening, a ladder hinge construction carried by each door and em-

bodying bracket arms pivoted to the silo wall between adjacent door openings, bracket arms pivotally connected to the door, link connections between said bracket arms, and means associated with the brackets carried by the door for holding the door in a closed and locked position.

4. In a silo, wherein the silo wall is provided with vertically alined spaced door openings, and wherein a separate door is associated with each opening, a ladder hinge construction carried by each door and embodying bracket arms pivoted to the silo wall between adjacent door openings, bracket arms pivotally connected to the door, link connections between said bracket arms, the pivotal connections between the last named brackets and the door embodying axially shiftable shafts, a crank handle upon the inner end of the shaft, and a cam head upon the outer end of the shaft adapted to be moved laterally of the door opening for engagement with the silo wall for holding the door in a closed and locked position.

25 5. In a silo, wherein the silo wall is pro-

vided with vertically alined spaced door openings, an independently operating door associated with each opening and connected to the wall of the silo in a manner to move inwardly of the silo when shifted to an open 30 position, said door when opened occupying a position spaced upwardly of the associated door opening and substantially alined with and parallel to the adjacent upper door, and means selectively connected to the doors for 35 moving the same to an open position.

6. In a silo, wherein the silo wall is provided with vertically alined spaced door openings, an independently operating door associated with each opening and connected 40 to the wall of the silo in a manner to move inwardly of the silo when shifted to an open position, said door when opened occupying a position spaced upwardly of the associated door opening and substantially alined with 45 and parallel to the adjacent upper door, and a weight selectively connected to the doors for moving the same to an open position.

In testimony whereof I affix my signature.
CLETUS M. PUETZ.
